UNITED STATES PATENT OFFICE.

FRIEDRICH BOEDECKER, OF BRITZ, NEAR BERLIN, PRUSSIA, GERMANY.

PROCESS FOR THE PRODUCTION OF A CRYSTALLIZED ESTER OF THE STEARO-RICINATE-DIIODID.

1,381,057.

Specification of Letters Patent. Patented June 7, 1921.

No Drawing.

Application filed July 9, 1920. Serial No. 395,138.

To all whom it may concern:

Be it known that I, FRIEDRICH BOEDECKER, a citizen of the Free State of Prussia, in the German Republic, residing at Britz, 5 near Berlin, in the Free State of Prussia, Germany, have invented Improvements in Processes for the Production of a Crystallized Ester of Stearo-Ricinate-Diiodid; and I do hereby declare the following to be a 10 full, clear, and exact description of the same.

From the esters of the stearo-ricinate-diiodid up to now only methyl ester has been produced as a weak yellow colored oil (see reports of the *Deutsche Chemische 15 Gesellschaft* 46 page 2004). It has now been found that the ethyl ester can easily be produced in solid crystallized form which could not be foreseen with regard to the properties of the methyl ester mentioned 20 above.

The ester may be produced in two processes:

(1) Iodin is added to the stearo-ricinate $\text{CH}_3(\text{CH}_2)_5.\text{CHOH}.\text{CH}_2.\text{C}:\text{C}(\text{CH}_2)_7.\text{CO}_2\text{H}$, 25 which is known as octadecin —9-OL (12) acid (1) according to the Geneva nomenclature and the acid produced is reduced to ethyl ester.

According to the process of Arnaud and Posternack iodin in glacial acetic acid can 30 easily be added to the acid of the series $\text{C}_n\text{H}_{2n-4}\text{O}_2$. This reaction may also be transferred to the stearo-ricinate, the hydroxyl series of the stearo-ricinate however causes 35 different by-reactions (see reports of the *Deutsche Chemische Gesellschaft* 46 page 2091). On the one hand dark colored products are obtained while on the other hand the stearo-ricinate is subjected to acetylen- 40 ing, whereby the stearo-ricinate-diiodid obtained is always greatly polluted by oily admixtures. These by-reactions are said to be prevented by iodizing (*l. c.*) during 10 hours at ordinary temperature or a temper- 45 ature of 40°.

The reception of the iodin is quantitative, the diiodid obtained however is in this case also polluted with dark colored dirty products which substantially reduce the output 50 of pure crystallized diiodid as well as the constancy of the raw-diiodid with regard to solvents. The injurious influence of the glacial acetic acid will be seen in a far higher degree if endeavors are made to work 55 on large scale according to the said process.

It has now been found that the acetylening produced by the excessive glacial acetic acid at the usual temperature and the combined disturbing by-products may be prevented by iodizing in aqueous acetic-acid. 60 After removing some of the excessive iodin solid nearly colorless diiodid is obtained by crystallizing of the resulting mass and precipitating of the mother-lye. This diiodid may easily be crystallized and according to 65 the usual methods transferred into ethyl ester.

(2) Iodin is added to the ethyl ester of the stearo-ricinate according to the methods coming into consideration. 70

The ethyl ester is to be used for therapeutic purposes.

Example 1: 100 parts of stearo-ricinate are dissolved under very weak heating in about 250 parts of 75% acetic acid and the 75 calculated quantity of iodin is added to the solution at once. The solution is then stirred at ordinary temperature until all the iodin is dissolved. The resulting mass soon solidifies to a crystalline pulp. The same 80 volume of water is added and the quantity of excessive iodin which may be present is taken away by sulfurous acid. The nearly or quite white stearo-ricinate-diiodid obtained is sucked off and washed with water. 85 The preparation after being once crystallized is perfectly clean. It will be dissolved in excessive pure alcohol, whereupon the solution is saturated in the cold with hydrochloric acid-gas and the resulting mixture 90 left to itself for several hours. Then the ester is precipitated with water and after drying crystallized out of low boiling benzin. The ester is in this way obtained in the form of colorless well formed needles 95 which melt at a temperature of 31°. The new combination is insoluble in water, easily soluble however in nearly all organic solvents.

Example 2: 125 g. iodin are admitted in 100 a concentrated solution of 100 g. of stearo-ricinate-ethyl-ester in glacial acetic acid. After stirring for 1 or 2 hours under a low heat all the iodin is solved. The dark brown colored solution after a longer stay 105 is precipitated with water and the separated heavy oil is washed with water. When cooling it solidifies rapidly and is crystallized out of spirit or ligroin.

Having now described and ascertained the 110

nature of my invention and the manner in which the same is to be performed I now declare what I claim and desire to secure by Letters Patent of the United States:

- 5 1. A crystalline ester of stearo-ricinate-diiodid having valuable therapeutic qualities, the ester being the ethylester of stearo-ricinate-diiodid.
- 10 2. A process for the production of a crystalline ester characterized in this that first

iodin in the presence of aqueous acetic-acid is added to the stearo-ricinate and the latter then transferred to the ethyl-ester.

In testimony whereof I have signed my name to this specification in the presence of 15 two subscribing witnesses.

DR. FRIEDRICH BOEDECKER.
